CLAIM

The ornamental design for a carrying case for aerosol generating consumables, as shown and described.

DESCRIPTION

FIG. 1 is a front, top, and left side perspective view of a first embodiment of a carrying case for aerosol generating consumables showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front, top, and right side perspective view thereof in a use condition.

FIG. 9 is a front, top, and left side perspective view of a second embodiment of a carrying case for aerosol generating consumables showing the new design.

FIG. 10 is a front elevational view thereof.

FIG. 11 is a rear elevational view thereof.

FIG. 12 is a top plan view thereof.

FIG. 13 is a bottom plan view thereof.

FIG. 14 is a right side elevational view thereof.

FIG. 15 is a left side elevational view thereof; and,

FIG. 16 is a front, top, and right side perspective view thereof in a use condition.

The broken lines depict portions of the carrying case for aerosol generating consumables that form no part of the claimed design.
